(57) **CLAIM**

The ornamental design for an ultrasound apparatus for dental use, as shown and described.

DESCRIPTION

FIG. 1 is a right perspective view of an ultrasound apparatus for dental use according to the new design.

FIG. 2 is a left perspective view of the ultrasound apparatus for dental use according to the new design.

FIG. 3 is a back view of the ultrasound apparatus for dental use according to the new design.

FIG. 4 is a front view of the ultrasound apparatus for dental use according to the new design.

FIG. 5 is a right side view of the ultrasound apparatus for dental use according to the new design; and,

FIG. 6 is a left side view of the ultrasound apparatus for dental use according to the new design.

The broken lines in the Figures illustrate portions of the ultrasound apparatus for dental use that form no part of the claimed design.
